ATTORNEY
INVENTOR.

UNITED STATES PATENT OFFICE.

CHARLES F. KLEMP, OF EL MONTE, CALIFORNIA, ASSIGNOR OF ONE-HALF TO CARL KLEMP, OF EL MONTE, CALIFORNIA.

BURGLAR ALARM.

Application filed June 25, 1928. Serial No. 287,986.

This invention relates to burglar alarms and more particularly to a burglar alarm adapted to be applied to a door or a window which may be set to fire a blank cartridge when the door or window is opened.

The general object of my invention is to provide a burglar alarm of the character stated which will be simple in construction, inexpensive and efficient in operation.

Other objects and advantages will appear hereinafter and while I show herewith and will describe a preferred form of construction, I desire it to be understood that I do not confine my invention to such preferred form but that various changes and adaptations may be made therein without departing from the spirit of my invention as hereinafter claimed.

Fig. 1 is an elevation of a door with my burglar alarm shown applied thereto.

Fig. 2 is an elevation of a window showing my invention applied thereto.

Fig. 3 is a fragmentary plan view of the sash of a window showing my invention applied to the sash.

Fig. 4 is a side elevation of my invention on an enlarged scale showing the locking pin in position locking the firing pin retracted and in operative position.

Fig. 5 is a front elevation of my invention as illustrated in Fig. 4.

Fig. 6 is a front elevation of my invention with the holding pin removed and the trigger resting upon the trigger holding arm to hold the firing pin retracted while the door or window is closed.

Fig. 7 is a front elevation of my invention showing the trigger escaped from the trigger holding arm and the blank cartridge fired by the firing pin when the door or window is opened slightly.

Fig. 8 is a side view of the locking pin.

Fig. 9 is a fragmentary side view of my invention and the door to which it is applied, showing the door slightly open and the trigger escaped from the holding arm.

Corresponding parts are designated by the same reference characters in all the figures.

My invention includes generally a base 1, a barrel 2, firing pin 3, trigger 4, firing pin spring 5, trigger clip 6, trigger holding arm 7, and locking pin 8.

The barrel 2 is secured on the base 1 by means of screws 9 and 10 driven through apertured flanges 11 and 12 formed on the

lower and upper ends respectively of the barrel.

The clip 6 is formed with a base member 13 and an offset member 14, which base member is secured to the upper end of the base 1 by screws 15 so that the trigger 4 may pass under said offset member 14 when the firing pin 3 and trigger are retracted. The offset member 14 is provided with an aperture 16 which registers with an opening 17 in the base 1, through which apertures and opening the locking pin 8 is introduced under the trigger 4 to lock the trigger and firing pin 3 retracted in inoperative position as shown in Figs. 4 and 5.

The trigger holding arm 7 is formed at one end with a screw 18 while its other end 19 is bent downwardly.

The spring 5 is connected at one end to one of the screws 9 at the lower end of the barrel 2 while the other end of the spring is connected to the trigger 4 at 20.

When my invention is applied to a door 21, the base 1 is secured to the inside of the door adjacent the swinging edge thereof, while the trigger holding arm 7 is secured to the door jamb adjacent the base 1, so that the trigger 4 may rest upon said arm to hold the firing pin retracted while the door is closed.

The barrel 2 near its lower end is cut away in front to provide an entrance 22 through which a blank cartridge 23 may be inserted into the lower end of the barrel with the rim 24 of the cartridge resting upon the lower edge of the entrance 22, whereby the cartridge is held in position in the barrel to be fired.

When the device is not in use the firing pin 3 may be raised and the locking pin 8 inserted through the aperture 16 and opening 17 under the trigger 4 to hold the firing pin retracted as shown in Figs. 4 and 5 so that the door or window sash may be opened and closed without firing the cartridge.

To set the device for operation the locking pin 8 is removed from under the trigger 4 and the trigger allowed to rest upon the holding arm 7 when the door is closed as shown in Fig. 6. Upon opening the door slightly the trigger will escape from the holding arm 7 (Figs. 7 and 9) and the trigger and firing pin 3 will be projected downwardly with considerable force by the spring 5, whereupon the point 24 of the firing pin engaging the

head of the cartridge will fire the same, the noise of which will give warning of a burglar entering the door.

The device is applied to a window by securing the base 1 to the upper side of the upper frame member of the lower sash and securing the holding arm 7, by means of its screw 18, in the upper side of the lower frame member of the upper sash in position to be engaged by the trigger 4 to hold the firing pin 3 retracted while the sash are closed (Fig. 3). Upon raising the lower sash or lowering the upper sash, the trigger 4 will escape the arm 7 and the firing pin 3 will be projected by the spring 5 to fire the cartridge as above described.

I claim as my invention:

A burglar alarm, adapted to be applied

to a door or window comprising means for holding a cartridge, a firing pin, a trigger on said firing pin, a spring connected to said firing pin, a barrel to support and guide said firing pin, an arm for engaging said trigger to hold said firing pin retracted when the door or window is closed and from which arm said trigger escapes when the door or window is opened to permit said spring to project said firing pin to fire said cartridge, a clip under which the trigger extends when the firing pin is retracted and a locking pin, said clip being provided with an aperture through which said locking pin is inserted behind the trigger to lock the firing pin in inoperative position.

CHARLES F. KLEMP.
